UNITED STATES PATENT OFFICE

JACOB A. HORCH, OF LOS ANGELES, CALIFORNIA

MAIL BOX

Application filed January 16, 1929. Serial No. 332,799.

My present invention has reference to a mail box which is primarily, though not necessarily, designed for household use, and among the objects is the provision of a mail box which may be easily and quickly attached to a support, one in which the contents are fully protected from weather conditions; one which carries a swingable bail for supporting letters thereon and one which has arranged therein a tray upon which the letters are deposited and which when the hinged top is swung to open position will be elevated so that the contents of the box may be readily removed therefrom, the cover being provided with an opening for the insertion of the mail matter.

A still further object is the provision of a mail box that has a sloping top normally closed by a cover provided with a depending bail to which is attached a mail receiving tray, the said tray having at its bottom an eye that, when the cover is closed, is movable through an opening in the bottom of the box and is designed to receive therethrough the hasp of a lock, and further wherein the cover is protected by a plate in the nature of a shield, so that moisture is effectively prevented from entering the box, the box being further provided on its outer face with integrally formed means for a name plate and is provided with a peep-hole whereby the owner can readily perceive whether or not the box contains mail matter, while on its rear face the box is formed with a socket whereby the same may be attached to a bracket secured on a suitable support.

To the attainment of the foregoing, the invention consists in the improvement hereinafter described and definitely claimed.

40 In the drawings:

Figure 1 is a front elevation of a mail box in accordance with this invention.

Figure 2 is a substantially central transverse sectional view therethrough.

Figure 3 is an approximately vertical longitudinal sectional view through the improvement.

Figure 4 is a similar view with the cover open.

Figure 5 is a transverse sectional view on the line 5—5 of Figure 3.

My improved mail box is preferably constructed wholly of metal and has an outer coating of water proof material. The mail box 1 is of substantially rectangular formation except that the front 2 inclines outwardly from its bottom to its top. The back 3 of the mail box is extended a suitable distance beyond the top of the front and the sides 4 of the said box are cut at an angle from the upper edge of the back 3 to the upper edge of the front 2. The back 3 has riveted or otherwise securely fixed thereon the ends of the strap, the central portion of which being outwardly bulged to form the same with a socket 5 and this socket is designed to receive therethrough a bracket or other means that is attached to a support.

The outer face 2 of the box, adjacent to the top thereof, is provided with right-angularly arranged preferably bendable ears 6. These ears are formed by slitting the face 2. By reference to the drawings it will be seen that two comparatively narrow ears are arranged at the center of the box and extend toward each other and that the end ears are laterally arranged and also have their ends extending toward each other. Between these ears there is designed to be received the name plate of the owner of the box. Below the name plate the box is formed with a substantially V-shaped opening 7, which is comparatively small and this opening provides a peep-hole whereby the owner can ascertain whether or not mail matter is received in the box.

Normally resting on the bottom of the box but arranged for slidable movement in the said box there is a flanged tray 8. This tray provides a receptacle for letters or like mail matter and passing through the side flanges of the tray in a line with the bottom thereof, there is the central member 9 of a substantially U-shaped wire member or bail 10. The arms of the bail are pivotally connected to depending ears 11 on the inner face of the cover 12 for the box. The cover 12 has its sides flanged, and the said flanges are pivotally connected, as at 13, to the sides 4 of the

box, adjacent to the upper or elevated rear end thereof. The cover 12 extends a suitable distance beyond the front of the box and the said cover is formed with an opening 14 whereby mail matter may be inserted into the box.

The ears 12 are preferably formed by slitting the cover both longitudinally and transversely and bending the slits inwardly.

In order to protect the openings in the cover 14 I arrange thereover a flanged protector plate 15. The plate 15 has its side flanges of a greater width than the side flanges of the cover and the outer or lower edge of the plate is formed with an angle extension 16 for directing water off of the said plate and away from the face or front of the box. The rear edge of the protector plate 15 is also flanged, as at 17, to cover the upper and elevated edge of the box.

The pivots 13 are formed on the inwardly extending ends of the arms of a wire bail 18. The central or connecting element for the bail is rounded away from the side ears thereof and is arched upwardly, as at 19, to afford with the ears gripping elements for newspapers, magazines and the like.

The central portion 9 of the substantially U-shaped wire member that I have termed the inner bail 10 is centrally rounded upon itself to form the same with an eye 20 that extends through alining openings in the bottom of the tray and in the bottom of the box and this eye, as disclosed by dotted lines in Figure 1 is adapted to be engaged by the hasp of a lock. When the lock is applied the cover is effectively sustained upon the box although the outer or protective face may be raised so that the owner may insert mail into the box. When the lock, indicated by the numeral 21, is removed the cover may be swung to its outward and open position and by virtue of such swinging the letter-receiving tray will be elevated in the box so that the contents thereof may be readily accessible and easily removed from the box.

The simplicity of my construction and the advantages thereof will, it is thought, be understood and appreciated by those skilled in the art to which such invention relates without further detailed description although I desire it understood that I do not wish to be restricted to the precise details herein set forth and, therefore, hold myself entitled to make such changes therefrom as fairly fall within the scope of what I claim.

Having described the invention, I claim:

A mail box comprising a vertically disposed and tapering casing provided with an opening in the bottom thereof and having the upper end fully open to provide an entrance, a pivoted cover for closing the entrance, a plate slidable in the casing and having an aperture aligning with the opening in the bottom wall, upstanding flanges on the

plate and fitting against the walls of the casing when the plate is in engagement with the bottom wall to provide a follower for receiving the lower ends of mail articles while in the casing, a substantially U-shaped bail including arms and a web portion extending through a pair of said flanges in close proximity to the plate and bent to provide a loop member extendible through the aperture and opening to receive a removable fastener, and means pivoting the arms to the cover.

In testimony whereof I affix my signature.

JACOB A. HORCH.
